UNITED STATES PATENT OFFICE.

HAROLD L. LEVIN, OF NUTLEY, NEW JERSEY, ASSIGNOR TO THE FLINTKOTE COMPANY, OF BOSTON, MASSACHUSETTS, A CORPORATION OF MASSACHUSETTS.

MANUFACTURE OF WATERPROOF FIBROUS PRODUCTS.

Application filed September 17, 1928. Serial No. 306,478.

This invention relates to improvements in the manufacture of waterproof or moisture-proof fibrous sheets, and is particularly concerned with improvements in methods recently adopted for producing waterproof or moisture-proof sheets by combining waterproofing material with the sheet or the plies composing the same, in the form of a dispersion thereof in an aqueous medium.

10 One of the improved methods of thus incorporating waterproofing material which is now being employed on a large commercial scale, comprehends the application of the aqueous dispersion of the waterproofing material in the form of a film or layer applied to one surface of a wet ply, or between adjoining surfaces of a plurality of wet plies combined to form a multi-ply sheet, simultaneously with the formation of said plies, the interposed film or layer of waterproofing material functioning as a septum or barrier precluding penetration of water or moisture therethrough. Products of these processes are particularly suitable for the manufacture of 25 fibrous containers for packaging various articles of food or the like which must be kept dry or at a constant degree of moisture content.

My invention relates more specifically to 30 improvements in processes of the type last described, and has as one of its principal objects the provision of a system for more uniform control in the application of the dispersion of the waterproofing material to the wet web or webs, the purpose being to secure a definite and pre-determined amount of waterproofing material per given area of the sheet, and to effect an even distribution of this amount of the waterproofing material 35 over such area in a layer or film of uniform thickness. This control in the operation is accomplished, in accordance with my present invention, by providing means for controlling the feed of the dispersion of waterproofing material to the instrumentality for applying the same to the web or webs, and by providing automatic means whereby the concentration of the waterproofing material in the last named instrumentality is maintained 40 at a substantially constant value.

Another object of my invention resides in the provision of mechanism for effecting a rapid change from one rate of feed of the waterproofing material to another, without necessitating stoppage of the machine, or in

any way interrupting the continuity of the operation.

A still further object of my invention is to provide for a more orderly operation of this type of process, to the end that losses incurred by frequent shut-downs may be avoided, and the operation carried on without the employment of skilled labor or supervision.

Other objects and advantages of my invention will be apparent to those skilled in the art from the following description and the accompanying drawings, showing one arrangement of parts which I have found satisfactory for accomplishing the objects of my invention.

In the drawing Fig. 1 shows, partly in elevation and partly in section, the relative position of the feeding mechanism and the mechanism for applying the waterproofing material, the feeding device being shown in section.

Fig. 2 is a sectional view taken along line 2—2 of Fig. 1.

Fig. 2^a is a detail of one of the orifice plates.

Fig. 3 is a sectional view taken along the line 3—3 of Fig. 1.

Fig. 4 is a view in section showing generally the arrangement of the instrumentality for applying the waterproofing material to the sheet.

Fig. 5 is a vertical sectional view taken along line 5—5 of Fig. 1.

Figs. 6 and 7 are fragmentary details of certain parts appearing in Figs. 4 and 5.

Fig. 8 is a diagrammatic representation showing the dispersion supply means with its pipe connections to the mechanism shown in Fig. 1.

Fig. 9 is a tabulation of figures applicable to a machine operated in accordance with my invention.

Referring in detail to the drawings, the letter A designates generally the feed control device and the letter B indicates generally the device for applying the dispersion of waterproofing material to the wet fibrous web as it is being carried by the usual blanket from the forming cylinder. The waterproofing material which may be employed for carrying out my invention is preferably an aqueous dispersion of normally non-fluid bitumen, such as paraffin, resin, asphalt or the like having a melting point of say, between 100 to 240° F., more or less, the bitumen being dispersed in an aqueous medium by means of a dispersing

85

90

105

110

agent, such as clay or any other suitable colloid. The dispersion may be fed to the feed control box A from the storage tank S (Fig. 8) by means of a pump P connected with the 5 valved pipes 2 and 3 as shown in Fig. 8. Adjacent the point of its connection with the feed control box A, the pipe 3 may have connected thereto a conventional form of screen trap 4, having positioned therein an open 10 ended cylindrical screen 5, as shown, spaced from the inner surface of the pipe 4 to provide an annular space 7 therein. The dispersion being fed to the control box A through the pipe 3, passes downwardly on the interior 15 of the screen 5, and filters through the screen, to thus remove lumps of objectionable size. The material then flows by way of the annular space 7 to the discharge end 8 of the pipe 3, into the feed control device A. Near the bottom 20 of the trap 4 there may be fixed any convenient form of valve 5^a for removing sediment.

The feed control device A is constructed, as shown, of an enlarged chamber 10 having a 25 smaller discharge chamber 11 joined at one end thereof and separated therefrom by the end wall 12. Mounted within the chamber 10 is an overflow pipe 13, the lower end of which fits snugly within the upper end of a 30 fixed nut 14. The lower half of the fitting 14 is internally threaded to receive the upper external threading of a discharge pipe 15, suitably valved for connection with the storage tank S or the pump P. The arrangement 35 of the overflow pipe 13 is such as to maintain a constant level of dispersion liquid within the chamber 10, and the pipe is adapted for ready removal from the fitting 14 so as to lower rapidly the liquid level in the event 40 this becomes necessary. The emulsion fed to the chamber 10, before being delivered therefrom to the discharge chamber 11, may be screened by the screening device 17 positioned within guides 18, fixed in an inclined 45 position to the side walls of chamber 10 as shown. Any further lumps of objectionable size, removed by screen 17, will gradually settle, collect between removable baffle plates 19 fixed to the bottom of the chamber and can 50 be removed by means of pipe 20.

In order to secure a constant and predetermined rate of feed of dispersion material to the applying device B, the end wall 12 of the chamber 10 is formed with an enlarged opening 55 21, the center of which is at a fixed and predetermined level, below the upper end of pipe 13. For the purpose of regulating the flow of material through the opening 21 I provide, in accordance with my invention, 60 plates 22, each formed with an orifice 23, the center of which is substantially in alignment with the center of the opening 21, when the plate is in operative position within the guideways 24 fixed to the interior of the end 65 wall 12 as shown in Figs. 1 and 2. As will be

evident, the rate of flow of dispersion liquid from the chamber 10, under the hydrostatic head of pressure, will depend upon the size of the orifice in the plate 22, and I, therefore, 70 provide a series of plates, the orifices of which vary in size between any desired limits. I preferably provide two guideways 24 and show in Figs. 1 and 2, a separate plate mounted in each guideway. The purpose of two guideways, is to enable a plate having an 75 orifice of one size to be fixed in position before the removal of another plate which has previously been in operative position. If it is desired to increase rapidly the rate of discharge a plate 22^a, having a correspondingly larger opening will be inserted in the guideway behind the plate 22, whereupon the plate 22 may be removed to thereby render effective the larger opening in the plate 22^a. Manifestly, should it be desired to subsequently increase or decrease the rate of discharge provided by the orifice in the plate 22^a, another plate with an orifice of the desired size may be then inserted in the guideway in front of the plate 22^a, whereupon the latter may be removed. By thus making provision for inserting one plate in operative position before removing another, I am enabled to prevent any sudden momentary discharge of liquid through the enlarged opening 21, as would be the case if it were necessary to remove one plate before another could be placed in proper position.

The dispersion material thus delivered at a constant and predetermined rate by the 100 orifice plate is discharged into the small chamber 11 and is adapted to be fed therefrom by the pipe 25 to the instrumentality B, for applying the dispersion to the wet web.

The lower end of the pipe 25 may terminate a slight distance above the upper end of a sight feed funnel 26, mounted at the upper end of pipe 27 for delivering the dispersion material to the applying mechanism B. The pipe 27 is connected with the compartment 29, formed to one side of the vat 28 and separated therefrom by a partition wall 30, having spaced discharging ports 31 therein, through which the material fed to the compartment 29 may enter the vat 28.

The dispersion material in the vat 28 is adapted to be applied to the web by means of a roll device 40. As shown in Figs. 4 to 7, this device preferably comprises a pipe or cylinder 41 of any suitable material, and 120 grooved longitudinally thereof, as at 42, at equally spaced points around its external periphery, for the reception of narrow strips 43 which are adapted to fit edgewise vertically within the grooves 42 and extend for a 125 substantial distance beyond the periphery of the pipe or cylinder 41, so as to provide a series of longitudinally extending and equally spaced points of support for a foraminous plate or screen 44. The screen 130

or wire 44 may be wound around the cylinder and secured in any convenient manner to the strips 43. The pipe or cylinder 41 is fixed to a shaft 45, mounted for rotation and suitably 5 journaled as at 46 in the bearing walls 47 spaced from the end walls 47^a of the vat 28. I find it advantageous to thus locate the bearings for the shaft 45 at a substantial distance from the walls 47^a, since this effectually 10 prevents accumulation of dispersion liquid around the bearings and consequent clogging thereof. The shaft 45 may be supported by any convenient form of packing 48 in the end walls 47^a. End plates 49 having slots 15 49^a in the peripheries thereof, to correspond with the strips 43, may be driven over the hub of the trunnions 49^b. The screen or wire 44 is designed to pick up, during its rotation within the liquid in the vat 28, the dispersion 20 material in the form of a film which may then be transferred during the continued rotation of the wire, to the wet fibrous web as the latter passes over the roll and in contact with the screen or wire.

25 It will be appreciated from what has already been said, that the dispersion material, comprising as it does water in the external phase thereof, may be diluted to substantially any desired extent. In carrying out my invention, I utilize this property of the miscibility of the dispersion with water to maintain throughout the operation of the mechanism, a constant degree of dilution of the dispersion maintained in the vat 28, so as to secure there-

30 35 by at all times, a predetermined uniform rate of deposition of dispersion upon the fibrous web by the roll 40. By maintaining a constant volume of liquid within the vat 28 and feeding thereto at a definite rate from the feeding device A the dispersion liquid containing a definite quantity of waterproofing material per unit volume, it is possible by my invention to determine for any given paper making machine, the exact amount of waterproofing material that will be deposited per unit area of the sheet.

40 Thus, I have shown in Fig. 9 a series of tabulations based upon a number of different sized orifices in the plates 22, beginning with a diameter of nine-sixteenths of an inch, and increasing by one-sixteenth inch increments to one and one-sixteenth inches. The rate of flow of dispersion through each of these orifices being ascertained, and the composition 45 of the dispersion being known, one may readily calculate the rate of flow of the asphalt or other waterproofing ingredient. In the specific example forming the basis of the tabulations, the dispersion was one which contained substantially two and one-half pounds of asphalt per gallon of dispersion, and the corresponding rates of asphalt flow are shown in Fig. 9. The amount of waterproofing ingredient thus delivered, that will be deposited 50 per unit area of the fibrous web, will depend

upon the linear speed of the paper making machine. Knowing then the linear speed of the machine and the width of the paper being produced, by calculating the area of paper produced and passed over the applying device B per unit interval of time, it is then merely a matter of mathematical calculation to arrive at the figure representing the pounds of asphalt or other waterproofing ingredient that would be applied per unit area to the sheet at such speed, for each of the different rates of flow of the waterproofing material from the feeding device A, corresponding to the several different orifices in the plates 22.

55 Fig. 9 shows the results of such calculation for the various size orifices as already indicated, when employed in conjunction with a paper making machine of 88" width, the linear speed whereof may vary from 60 to 250 feet per minute.

60 It will be obvious to those skilled in the art, that assuming a machine of this width to be operating at a speed of 200 feet per minute, and the dispersion being supplied by the feed box A through a plate having a nine-sixteenth inch orifice, the finished product would have distributed thereover an asphalt film of a thickness such as to weigh substantially five and eight-tenths pounds per thousand square feet. Now should it be desired to increase the thickness of the asphalt layer produced at this machine speed to a value, of say, 10.5 pounds of asphalt per thousand square feet, it would be necessary, as indicated from the tabulations, merely to replace the plate having a nine-sixteenth inch orifice with one having a three-fourths inch orifice. It will be evident also, of course, that for any given weight of asphalt or other waterproofing substance per thousand square feet should it be desired to operate the machine at a lower or higher speed, this may be accomplished merely by replacing the plate with one having a smaller or larger orifice, as the case may be, in accordance with the tabulations. Thus, to alter the operation from a machine speed of 200 linear feet per minute, with an asphalt deposition of 10.5 pounds asphalt per thousand square feet, to a machine speed of 170 feet per minute with substantially the same amount of asphalt deposited, the three-fourth inch orifice plate would merely need to be replaced by an eleven-sixteenth inch orifice plate, as will appear from Fig. 9.

65 In order to maintain the constant volume of liquid within the vat 28 for the purposes indicated, I preferably supply the dispersion at such a concentration as would be too thick or viscous for application to the wet web under the particular conditions of machine speed so that some degree of dilution will always be required in order to bring the dispersion liquid to the proper concentration under such conditions of operation. I have found, that in general, a concentration of more than two

pounds of asphalt per gallon of the dispersion is too thick for convenient operation, particularly inasmuch as at such consistency the application roll 40 tends to pick up the dispersion too rapidly during the rotation thereof. In carrying out the invention therefore, I supply the dispersion at an excessive concentration to the feeding device A and deliver the same therefrom at the regulated rate of flow, as already described, so that the requirement for dilution affords means for automatically maintaining a constant volume of liquid within the vat 28. As will be seen from Fig. 1, the dispersion delivered from the feed device A, by the pipe 25 to the sight feed funnel 26, is fed to the vat under a hydrostatic head of pressure. The pipe 27 through which the dispersion is thus being fed to the vat has connected thereto a suitable valved inlet 50, leading to any convenient source of water supply as indicated at 51, and by means of the head of pressure under which the dispersion is being fed through the pipe 27, the water supplied at 50 is drawn into the pipe 27 by the suction produced, and serves to dilute the dispersion being fed to the vat. The water inlet at 50 may be provided with any suitable form of liquid level regulating device or it may simply have its upper open end terminating at any desired level, corresponding to the liquid level desired to be maintained within the vat 28, in which case any excess water or surplus liquid overflowing at 50 may be recovered in the pan 52 and conveyed away by pipes to any desired point. It will be understood that should the level of liquid within the vat 28 fall below the desired level, with a resultant concentration or thickening of the dispersion liquid therein, it would result in automatically increasing the inflow of water at 50 to thus provide a corresponding increase in the dilution until the volume of the liquid in the vat increased to an extent sufficient to return to the desired level therein. Hence, by the arrangement described, any decrease of the liquid level in 28 below the desired point will be substantially instantly and automatically compensated for by a corresponding addition of water through the inlet 50 without materially affecting the rate of application of waterproofing ingredient by the roll 40 to the web.

While I have described my invention in connection with the production of waterproof or moistureproof sheets, it will be understood, of course, that the principle thereof may be utilized with advantage in the manufacture of oilproof or greaseproof fibrous products by a proper selection of oil or grease proofing ingredient.

I claim as my invention:

1. In mechanism for applying waterproofing material to a wet fibrous web, the

combination with a foraminous mould for applying an aqueous dispersion of said waterproofing material to said web at a constant rate, of means for diluting the dispersion thus supplied, and means for maintaining a constant rate of dilution of said dispersion. 70

2. In mechanism for applying an aqueous dispersed material to a wet fibrous web, the combination with a foraminous mould for applying the aqueous dispersed material to the web, of means for supplying dispersed material to said mould at a constant rate, said means comprising a supply box and adjustable means for discharging material therefrom at a constant volume per unit interval of time. 75

3. In mechanism for applying waterproofing material to a wet fibrous web, the combination with a foraminous mould for applying an aqueous dispersion of waterproofing material to the web, of means for supplying dispersion to said mould at a constant rate, said means comprising a supply box having an adjustable discharge opening proportioned to deliver a constant volume of 80 said dispersion from said supply box per unit interval of time. 85

4. In mechanism for applying waterproofing material to a wet fibrous web, the combination with a foraminous mould for applying an aqueous dispersion of waterproofing material to the web, of means for supplying dispersion to said mould at a constant rate, said means comprising a supply box, means for maintaining dispersion therein at a predetermined level, said supply box having a discharge opening in one wall thereof and below the level of liquid maintained therein, and means for regulating the rate of flow of liquid through said discharge opening. 95

5. In mechanism for applying waterproofing material to a wet fibrous web, the combination with a foraminous mould for applying an aqueous dispersion of waterproofing material to the web, of means for supplying dispersion to said mould at a constant rate, said means comprising a supply box, means for maintaining dispersion therein at a predetermined level, said supply box having a discharge opening in one wall thereof and below the level of liquid maintained therein, and means for regulating the rate of flow of liquid through said discharge opening, said last named means comprising removable plate members, having orifices therein proportioned to deliver the desired rate of flow of liquid per unit interval of time. 110

6. In mechanism for applying waterproofing material to a wet fibrous web, the combination with a foraminous mould for applying an aqueous dispersion of waterproofing material to the web, of means for supplying dispersion to said mould at a constant rate, said means comprising a supply box, an overflow pipe in said box for maintaining disper- 120

sion therein at a predetermined level, said supply box having a discharge opening in one wall thereof below the level of liquid maintained therein, means for regulating the 5 rate of flow of liquid through said discharge opening, and means for diluting the dispersion thus supplied, to a constant volume.

7. In apparatus of the class described, the combination with means for applying bituminous dispersion to a preformed wet fibrous web, of means for supplying said dispersion to said first means at a constant rate and means for diluting the dispersion thus supplied to a constant volume maintained in said 15 applying means.

8. In mechanism for applying waterproofing material to a wet fibrous web, the combination with a foraminous mould for applying an aqueous dispersion of waterproofing 20 material to the web, of means for supplying dispersion to said mould at a constant rate, said means comprising a supply box and adjustable means for discharging material therefrom at a constant volume per unit 25 interval of time, and means for diluting the dispersion thus supplied, to a constant volume.

9. In mechanism for applying waterproofing material to a wet fibrous web, the com-

bination with a foraminous mould for applying an aqueous dispersion of waterproofing material to the web, of means for supplying dispersion to said mould at a constant rate, said means comprising a supply box having an adjustable discharge opening proportioned to deliver a constant volume of said dispersion from said supply box per unit interval of time, and means for diluting the dispersion thus supplied, to a constant 30 volume.

10. In mechanism for applying waterproofing material to a wet fibrous web, the combination with a foraminous mould for applying an aqueous dispersion of waterproofing material to the web, of means for supplying dispersion to said mould at a constant rate, said means comprising a supply box, means for maintaining dispersion therein at a predetermined level, said supply box having a discharge opening in one wall thereof and below the level of liquid maintained therein, means for regulating the rate of flow of liquid through said discharge opening, and means for diluting the dispersion thus supplied to a constant volume.

In testimony whereof I affix my signature.

HAROLD L. LEVIN.
